UNITED STATES PATENT OFFICE

WILLIAM H. WENDT, OF LITTLE FALLS, MINNESOTA

COLLAPSIBLE SHAFT

Application filed May 7, 1927. Serial No. 189,590.

This invention relates to new and useful improvements in collapsible shafts, generally, and more particularly relates to such shafts adapted for use in paper mills to receive paper which is wound thereupon in the form of a web. After the paper has thus been wound or rolled upon the shaft, it is removed therefrom in the form of a large roll, and it is therefore desirable that the shaft upon which the paper is wound, is constructed in such a manner that it may be collapsed or reduced in diameter to permit the easy removal of the roll of paper therefrom.

An object of this invention is to provide a collapsible shaft, comprising two sections normally spaced apart and retained in true diametric relation, and one of said sections being translatable axially with respect to the other section to cause the shaft to collapse to a smaller diameter, when moved in one direction, and to cause it to expand to normal diameter, when moved in the opposite direction.

A further object of the invention is to provide such a shaft comprising two sections interlockingly engaged with each other, and one of the sections being adapted for radial and longitudinal movement to decrease the diameter of the shaft, when moved in one direction, to permit the removal of a roll of paper or other material therefrom.

Other objects of the invention are; to provide a collapsible shaft comprising a stationary section and a movable section, and the stationary section having a plurality of cam members secured thereto and engageable with means on the movable section to expand the shaft to normal diameter, and the movable section having a plurality of transversely disposed recesses in the adjacent faces thereof adapted to receive said cam elements to cause the collapse of the shaft; to provide such a shaft having the adjacent edges of the sections thereof interlockingly engaged with one another lengthwise thereof to prevent the separation of the two sections, when the shaft is removed from its bearings; to provide means for longitudinally moving one of the shaft sections for the purpose of expanding and collapsing the shaft; and in the general construction of the shaft which is very simple

and inexpensive and may therefore be manufactured at a minimum cost.

The particular object of the invention therefore is to provide an improved collapsible shaft.

Other objects of the invention will appear from the following description and accompanying drawings and will be pointed out in the annexed claims.

In the accompanying drawings there has been disclosed a structure designed to carry out the various objects of the invention but it is to be understood that the invention is not confined to the exact features shown, as various changes may be made within the scope of the claims which follow.

In the accompanying drawings forming part of this specification;

Figure 1 is an elevational view, showing the improved shaft mounted in suitable bearings;

Figure 2 is a longitudinal sectional view showing the shaft sections in normal expanded position;

Figure 3 is a similar view showing the shaft sections collapsed;

Figure 4 is a view similar to Figure 3, partially broken away, to show the channels provided in the adjacent edges of the shaft sections;

Figure 5 is an enlarged cross sectional view on the line 5—5 of Figure 2; and

Figure 6 is a similar view on the line 6—6 of Figure 3.

The novel shaft featured in this invention comprises a stationary section 11 and a movable section 12 normally spaced apart by a plurality of cam members 13, having their end portions seated in inwardly facing channels 14, provided adjacent the faces or edges 15 of the shaft section 11, as shown in Figure 5. The shaft section 12 is provided with outwardly facing channels 16 and tongues 17 which are received in the channels 14 in the stationary section 11. The shaft section 11 is also provided with inwardly facing tongues 18 which are received in the channels 16 in the shaft section 12, and are adapted to engage the tongues 17 to prevent the accidental separation of the two shaft sections, when

they are removed from their bearings 19 and 20, shown in Figure 1.

The adjacent faces or edges 21 of the shaft section 12 have transversely disposed recesses 5 or notches 22 provided at intervals therein, each of which has an inclined face 23 adapted to engage its complementary cam member 13, shown in Figures 2 and 3. The recesses 22 are of sufficient length to receive the cam members 13, as shown in Figure 3. In Figure 2, it will be noted, that the shaft section 12 is spaced from the section 11 as a result of the faces 21 of the section 12 being engaged with the cams 13. It will therefore be seen 10 that when the shaft section 12 is moved in the direction indicated by the arrow in Figure 2, that the faces 21 of the section 12 will be moved out of engagement with the cam members 13, and the latter will be received 15 in the recesses 22, after which the upper section will assume the position shown in Figure 3, with its faces coincident with the faces 15 of the shaft section 11, as shown in Figures 3 and 6. When the parts are thus positioned, the diameter of the shaft in one direction will be decreased, as indicated by the dotted lines in Figure 6.

The means provided for axially or longitudinally moving the shaft section 12 with 20 respect to the stationary section 11, is shown in Figures 2 and 3, and resides in the provision of elongated apertures 24 and 25 respectively in the shaft sections 11 and 12. These apertures are adapted to receive an 25 operating lever or member 26, having a stud or pin 27 secured thereto and adapted to engage one of the shaft sections to limit the insertion of the member through the apertures 24 and 25, shown in Figure 3. This 30 operating member functions as a lever to translate the upper section 12 with respect to the lower section, which will readily be understood, by reference to the right hand sides of Figures 2 and 3. The dotted lines in 35 Figure 2 illustrate the position of the lever before having moved the shaft section 12, and the full lines in Figure 3 illustrate the position of the lever after having translated the shaft section 12 to collapse the shaft.

50 The means provided for locking the two shaft sections in their normal expanded positions is shown in Figure 2 and comprises an annular collar 28 having a lock screw 29 mounted therein and adapted to securely lock 55 together the two sections. The lower terminal of the lock screw is preferably engaged with a block 30 of a relatively soft metal, to prevent the screw from damaging or marring the surface of the shaft section 60 12, when the screw is in locking position. The collar 28 also functions as a stop collar to prevent longitudinal movement of the shaft in one direction, when positioned in the bearings 19 and 20. Stop means are also 65 preferably provided adjacent the opposite

ends of the shaft sections to prevent longitudinal movement of the shaft in the opposite direction. Such means consists in the provision of stop elements 31 and 32 being secured respectively to the shaft sections 11 and 12, as shown in Figures 1, 2, and 3. These members are semi-circular in form, and, when the shaft sections are mounted in their bearings and are expanded to normal position, the members 31 and 32 form in effect 70 a collar adapted to engage one end of the bearing 20, to prevent longitudinal movement of the shaft sections. 75

When it is desired to collapse the shaft, the lock screw 29 is released, after which the operating lever 26 is inserted in the apertures 24 and 25 as indicated in dotted lines in Figure 2. It is then moved to the right to the full line position in Figure 3, thereby 80 relatively translating the upper section 12 upon the lower section, until the notches 22 are moved into registration with the cam members 13, thus causing the collapse of the shaft. (See Figures 2 and 3.) The shaft sections may as readily be expanded to their 85 normal position by simply moving the operating lever 26 in the opposite direction. A stop bar 33 is terminally secured to the stationary shaft section 11 as shown at the left hand side of Figures 2 and 3, adapted to 90 be engaged by the movable section to limit its axial movement in one direction. The section 12 has notches 34 adapted to receive the stop bar 33. 95

I claim as my invention:

1. A collapsible shaft comprising two semi-cylindrical sections normally retained in true diametric relation and adapted, upon relative axial movement of one of said sections, to collapse, the adjacent edges of said 105 sections being interlockingly engaged.

2. A collapsible shaft comprising two semi-cylindrical sections inseparably connected, means normally retaining said sections in expanded diametric relation, and one of said sections being translatable longitudinally upon the other section to cause the collapse 110 of the shaft.

3. A collapsible shaft comprising two sections interlockingly engaged with each other, means normally retaining said sections in expanded position and adapted upon axial movement of one of said sections in one direction, to cause the shaft to collapse, and when said section is translated in the opposite direction, to cause the shaft to expand to normal diameter, and sockets in said sections adapted to receive an instrumentality for relatively translating one of said sections upon the other. 115

4. A collapsible shaft comprising two elongated, semi-cylindrical sections inseparably connected together, cam elements secured to one of said sections and normally retaining said sections in expanded diametric relation, 120 125

and the other of said sections having a plurality of transversely disposed recesses adapted to receive said cam elements to cause the collapse of the shaft, when one of said shaft sections is translated axially with respect to the other section.

5. A collapsible shaft comprising two elongated, semi-cylindrical sections inseparably connected together, and cam elements secured to one of said sections and normally retaining said sections in expanded diametric relation, the other of said sections having a plurality of transversely disposed recesses adapted to receive said cam elements to cause the collapse of the shaft, and said shaft sections being adapted to receive an element for relatively translating one of said sections upon the other section.

6. A collapsible hollow shaft comprising a stationary section and a movable section, having their adjacent edges interlockingly engaged to prevent accidental separation of the two sections, when removed from their support, and transversely disposed cam elements secured to the stationary section and normally retaining the sections in spaced expanded position, and said movable section having a plurality of transversely disposed recesses adapted to receive said cam elements to cause the collapse of the shaft, when said movable section is translated longitudinally.

7. A collapsible hollow shaft comprising a stationary section and a movable section, having their adjacent edges channelled and interlockingly engaged to prevent accidental separation of the two sections, when removed from their support, and transversely disposed cam elements secured to the stationary section and normally retaining the sections in spaced expanded position, said movable section having a plurality of transversely disposed recesses adapted to receive said cam elements to cause the collapse of the shaft, when said movable section is axially translated in one direction, and said shaft section being adapted to receive an operating means for translating said movable section.

8. A collapsible shaft comprising semi-cylindrical, hollow sections, one stationary and the other axially translatable thereon, the stationary section having inwardly facing longitudinal channels adjacent the edges thereof and inwardly facing marginal tongues, said movable section having outwardly facing longitudinal channels adapted to receive said marginal tongues to prevent the accidental separation of the shaft sections, and means interposed between said sections adapted to cause the collapse of the shaft, when said movable section is translated in one direction, said means causing the expansion of the shaft to normal diameter, when said section is moved in the opposite direction.

65. 9. A collapsible shaft comprising semi-

cylindrical, hollow sections, one stationary and the other axially translatable thereon, said stationary sections having inwardly facing longitudinal channels and tongues, and said movable section having similarly shaped outwardly facing channels and tongues adapted to interlockingly engage the channels and tongues in said stationary section to limit the relative radial movement of said shaft sections and permitting relative longitudinal movement thereof, and cam devices associated with said sections to cause the collapse of the shaft, when the movable section is translated in one direction, and to cause the expansion of said shaft to normal diameter, when said section is moved in the opposite direction.

10. A collapsible shaft comprising a stationary and a movable section having their adjacent portions channelled and interlockingly engaged, and spaced cam elements secured in the channels of the stationary section, and said movable section having correspondingly spaced recesses adapted to receive said cam elements to effect the expansion and collapse of the shaft, when the movable section is relatively translated upon the stationary section, and said cam elements and recesses being concealed from view when the shaft sections are assembled.

In witness whereof, I have hereunto set my hand this 29th day of April, 1927.
